UNITED STATES PATENT OFFICE.

ROBERT TAYLOR JOHNSTON, OF SCOTCH PLAINS, NEW JERSEY.

PLANOGRAFIC-PRINTING PRESS.

1,075,575.

Specification of Letters Patent. Patented Oct. 14, 1913.

Application filed December 18, 1911. Serial No. 668,856.

To all whom it may concern:

Be it known that I, ROBERT TAYLOR JOHNSTON, a citizen of the United States, residing at Scotch Plains, in the county of Union and State of New Jersey, have invented certain new and useful Improvements in Planographic-Printing Presses, of which the following is a specification.

This invention relates to printing presses in general and more particularly to rotary presses and aims to produce a press of this general character which can be used either for two color printing on one side of the paper or for perfecting printing, *i. e.*, printing upon both sides of the paper in single colors.

It is also an object of my invention to provide a novel paper carrying or printing cylinder and feeding and delivery mechanisms and printing mechanism, all constructed and arranged to coöperate with said paper carrying cylinder so as to work in a most efficient, satisfactory and economical manner and capable of converting the press by a single, simple adjustment from a two color press to a perfecting press and vice versa.

Another object of the invention is to provide a machine which shall be of compact construction with the plate cylinders located in an easily accessible position, under the constant inspection of the operator and above the feeding and delivery mechanisms where they will not collect the paper dust which is constantly falling from the paper as it is fed along.

Other objects and advantages of the present invention will be apparent from the following description when considered in connection with the accompanying drawings illustrating one preferred embodiment thereof.

Referring to the drawings, the single figure is a side elevation of a press embodying one form of my invention.

On the drawings, at one end of the main frame 5 of the machine there is mounted the supply table 6 adapted to carry a supply of paper and upon the opposite end is located the delivery mechanism the structure of which will be hereinafter described. The paper carrying or transfer cylinder 7 is rotatably mounted on the frame of the machine. The surface of this cylinder is theoretically divided into an odd number of sections or portions by real or imaginary

lines of demarcation. The cylinder illustrated on the drawings comprises three sections designated as *a*, *b* and *c*, respectively, preferably separated one from the other by longitudinal grooves or depressions 8. Each individual section is equipped at its forward edge with grippers designated as 9, 10 and 11, respectively. The paper carrying cylinder is provided on its periphery at one end with a gear meshing with and driven by the gear 12 mounted on the main shaft 13. This shaft may be driven in any suitable manner but in the present instance I have shown for purposes of illustration a gear 14 mounted on the outer end of the shaft and meshing with the driven gear 15 connected with the shaft of a motor 16. It will be obvious, however, that any other suitable driving mechanism may be employed, if preferred. Each section of the paper carrying cylinder 7 is preferably covered with a rubber or impression sheet adapted to serve either as impression surfaces or transfer surfaces depending upon the manner in which the machine is operated.

The paper is fed from the supply table 6 to the carrying roll 7 by a feeding cylinder 17 journaled on the main frame and provided on its periphery with a set of grippers 18. The circumference of the feed roll is equal to twice the distance between adjacent sets of grippers on the main paper carrying cylinder and said feed roll is driven at the same peripheral speed as the paper cylinder so that a sheet is delivered by the feed roll only to alternate sets of grippers on the paper carrying cylinder.

It will be obvious as the operation of the invention is better understood that other forms of feeding devices may be employed in lieu of the feeding cylinder shown, it being necessary, of course, however, that the timing of the feeding mechanism be such that the paper will be delivered to the paper carrying cylinder at proper predetermined times.

Upon the frame of the machine above the feeding and delivery mechanisms and on opposite sides of the paper carrying cylinder 7 are mounted a pair of plate cylinders 19 and 20. The peripheries of these cylinders are preferably divided into sections substantially equal in length to the sections of the cylinder 7, each plate cylinder being divided into two sections, upon one section

of which the impression plate is mounted, the remainder of the circumferences of the plate cylinder lying below the outer face of the plate so that it never contacts with the periphery of the cylinder 7. The plate cylinders are each driven at the same peripheral speed as the cylinder 7 so that obviously the plates carried thereby will coöperate at each revolution of the plate cylinders with alternate sections of the paper carrying cylinder. Ink is supplied to the plate cylinders 19 and 20 from ink fountains 21 and 22 through the intermediary of suitable distributing rolls designated generally by reference characters 23 and 24, respectively. A water fountain 25 of usual construction is mounted adjacent the cylinder 19 and a similar fountain 26 is mounted adjacent the cylinder 20, said fountains being adapted to supply water to the plates on the cylinders, as required.

A stripper roll 27 is mounted adjacent the cylinder 7 and on the opposite end of the machine frame from the feed cylinder 17, said stripper roll being equipped with suitable grippers 28 adapted to grip the edge of a sheet of paper delivered from the cylinder 7 so that said sheet is stripped from the carrying cylinder onto the stripper roll. The circumference of the stripper roll is substantially equal to the length of one of the sections of the carrying cylinder 7 and, since the peripheral speed of the stripper roll is equal to the peripheral speed of the carrying cylinder, it will be evident that the stripper roll makes three revolutions to each revolution of the carrying cylinder. After a sheet has been stripped from the carrying cylinder it is delivered upon the next revolution of the stripper roll to a delivery mechanism which may be of any well known or preferred construction but which, in the present instance, I have shown as comprising a chain 29 running around suitable sprockets 30 and 31 and equipped with a set of grippers 32 adapted to receive the edge of the sheet of paper from the grippers 28 and remove the sheet from the stripper roll as the grippers travel toward the sprocket 30. The chain 29 is driven from the stripper roll 27 by a gear connection or any other suitable driving mechanism, not shown.

A printing press constructed in accordance with the foregoing description is capable of use either as a two color press, printing on one side of the paper only or as a perfecting press and I will now describe the operation of a press embodying my invention; first—when used as a two color press and then, when used as a perfecting press: When used as a two color press the impression may be made on the paper either directly from the plates carried by the plate cylinders 19 and 20 or, the impression from these plates may be made on the rubber sheets carried by the

cylinder 7 and then transferred from the sheets to the paper. Assuming first, that it is desired to print directly from the plates onto the paper carried by the cylinder 7: A sheet of paper is delivered by the feeding cylinder 17 at the proper time to be engaged by the set of grippers 9. As the cylinder 7 revolves the sheet is laid upon the section *a* and is carried under the plate on the cylinder 20 which delivers its impression upon the outer face of the paper. The cylinders 19 and 20 are so adjusted that the plates of each are brought in contact with the section *a* and the plate carried by the cylinder 19 delivers its impression to the outer face of the paper on the section *a* over the impression delivered by the plate on the cylinder 20. The cylinders 19 and 20 are preferably supplied with ink of different colors with the result that two color printing is produced upon the paper passed successively under the plates. Since the circumference of the feeding cylinder 17 is substantially equal to two of the sections on the cylinder 7 it will be obvious that the next sheet of paper after the one delivered to the section *a* will be delivered to the section *a* and that during the running of the machine the sheets are always fed to alternate sections, the plate cylinders 19 and 20, also being of the same size as the feeding cylinder 17 and rotated at the same peripheral speed as the sectional cylinder 7, will coöperate with alternate sections of the cylinder 7, *i. e.*, the section *a* will first be printed by the cylinder 20; then by the cylinder 19; the section *b* will be skipped by both cylinders and the section *c* which has received a sheet of paper from the feeding cylinder 17 will next be printed by the cylinders 20 and 19, respectively. The stripper roll 27, the circumference of which is practically equal to the length of one of the sections, is adapted to operate only upon alternate sections of the cylinder 7 by reason of the fact that the grippers of this roll are timed to open and close upon alternate revolutions of the roll so that said stripper roll makes two revolutions at each stripping operation, *i. e.*, one revolution to strip the paper from the cylinder 7 and another revolution to deliver said paper to the delivery chain 29. It will thus be manifest that the feeding, delivery and plate cylinders are adapted to coöperate in succession with the section of the cylinder 7 and successively with alternate sections thereof.

When the press is employed as a two color offset press the impressions from the plates on the cylinders 19 and 20 instead of being made directly upon the paper carried by the cylinder 7, are delivered to the rubber transfer and impression sheets carried by the sections of the paper carrying cylinder, *i. e.*, the impressions of both plates are made upon the rubber sheet on section *a*, for in-

stance, before the paper is fed to said section and as the paper is laid on the section and is pressed between the section *a* and the surface of the feeding cylinder 17 the impression on the rubber transfer sheet is transferred to the face of the paper lying next to the sheet. In this instance, the stripper roll 27 is timed to remove the sheets from the roll 7 without permitting them to pass around the roll. In other words, the sheets are carried by the roll 7 only from the feeding cylinder 17 to the stripper roll 27 instead of making one complete revolution with the cylinder 7 and part of another as is done when the press is operated as a two color plate printing machine, as previously described.

When the machine is used as a perfecting press, *i. e.*, to print in single colors upon both sides of the paper, one of the plate cylinders 19 or 20 is timed to deliver its impression upon the transfer sheet of the cylinder 7 while the other plate cylinder is timed to deliver its impression directly upon the outer surface of the paper. Assuming that the cylinder 19 delivers its impression to the transfer sheet of the cylinder 7 and the cylinder 20 prints directly upon the paper, the operation will be as follows: The transfer sheet on the section *a* has received its impression from the cylinder 19. This impression is transferred to the sheet of paper delivered by the feeding cylinder 17 to said section under the pressure applied to the paper by the feeding cylinder. The paper is then carried around the cylinder 7 during its revolution and is brought into co-operative relation with the plate cylinder 20 which is timed to engage the section *a* and deliver its impression upon the outer face of the paper carried thereby. As the section *a* carrying the sheet of paper passes the cylinder 19 the plate of this cylinder is in inoperative relation with the section and the paper travels around to the stripper roll 27 where it is stripped from the cylinder 7 and subsequently delivered to the delivery mechanism 29.

As previously stated the plate cylinders 19 and 20, the feeding cylinder 17 and the stripper roll 27 all travel at the same peripheral speed as the sectional cylinder 7 and, since the circumference of the plate cylinders and the feeding cylinder are substantially equal to the length of two sections of the paper carrying cylinder, it will be obvious that every alternate section of the cylinder 7 is skipped by each of these cylinders and that these cylinders co-operate successively upon one section, skipping the next section, co-operating successively with the following section and so on, thus co-operating successively with alternate sections. The stripping roll also co-operates with the alternating sections by reason of the fact, as pre-

viously described, that said roll makes two revolutions at each stripping operation, stripping a sheet of paper from one section and delivering said sheet to the chain delivery 29 while the next section is passing 70 the stripper roll.

Any well known or preferred means such, for instance, as that disclosed in Patent No. 517,908, granted April 10, 1894, may be employed to operate the grippers on the feed cylinder, the paper carrying cylinder and the stripper roll, at the requisite times.

It is believed that my invention will be understood from the foregoing without further description and it will be obvious that 75 by adjusting either of the plate cylinders 180° on its axis the machine can be converted from a two color press into a perfecting press and that by properly timing the stripper roll the machine may be operated when 80 used as a two color press either as a two color plate printing press or a two color offset press, the paper in the one instance passing entirely around the cylinder 7 and in the other instance traveling only from the feeding cylinder 17 to the stripper roll.

While I have shown and described the general construction and arrangement of a press embodying my invention it will be obvious that the mechanical details of construction are capable of wide variation without departing from the spirit of the invention or sacrificing any of the material advantages thereof.

I claim:

1. In a printing press, the combination of a paper carrying cylinder having its circumference divided into an odd number of sections, a feeding and impression cylinder for delivering paper to said sectional cylinder, a stripper and delivery roll, and a pair of plate cylinders adapted to co-operate throughout a portion of their circumference with said sectional cylinder, said feeding and plate cylinders being constructed to revolve with respect to the sectional cylinder at a ratio of 3 to 2 whereby the individual sections of said sectional cylinder are brought alternately into co-operative relation successively with the feeding cylinder and the plate cylinders, and said stripper roll being constructed to revolve at a ratio of 3 to 1 with respect to the sectional cylinder and adapted to co-operate with alternate sections only of the sectional cylinder.

2. In a printing press, the combination of a paper carrying cylinder having its circumference divided into an odd number of sections, a feeding and impression cylinder having a circumference equal to the length of two of said sections, a pair of plate cylinders of substantially the same circumference as the feeding cylinder, each of said plate cylinders having an operative portion and an inoperative portion, and a delivery cylin-

4
der equal in circumference to the length of one of said sections, each of said plate cylinders, feeding cylinder and delivery cylinder being constructed and arranged to cooperate with the various sections of the paper carrying cylinder in alternation.

3. In a printing press, the combination of a paper carrying cylinder divided into an odd number of sections, a feeding and impression cylinder for delivering paper to the alternate sections of said paper carrying cylinder, a plurality of plate cylinders each

having an inoperative portion and an operative portion adapted to cooperate with alternate sections of said paper carrying cylinder, and a stripper and delivery device provided with grippers arranged to withdraw the sheets of paper from alternate sections of the paper carrying cylinder and deliver the same away from said cylinder.

ROBERT TAYLOR JOHNSTON.
